UNITED STATES PATENT OFFICE.

JOSEPH W. PHINNEY, OF BOSTON, MASSACHUSETTS, ASSIGNOR TO THE AMERICAN TYPE FOUNDERS COMPANY, OF NEWARK, NEW JERSEY.

DESIGN FOR A FONT OF TYPE.

SPECIFICATION forming part of Design No. 28,253, dated February 1, 1898.

Application filed August 19, 1897. Serial No. 648,837. Term of patent 7 years.

To all whom it may concern:

Be it known that I, JOSEPH W. PHINNEY, a citizen of the United States, and a resident of Boston, Massachusetts, have invented a certain new and useful Design for a Font of Gothic Type, of which the following is a specification.

My design for a font of Gothic type is clearly illustrated in the accompanying typographical impression.

The heavy shading and the square effect of the characters are the essential features of the design.

All the letters of the upper case with the exception of the letters J and Q are of a uniform height and depth. The right-hand inclined line of the letter A is heavy and the diagonal left-hand line is united to the right-hand line at the upper end. The two lines are connected by a light cross-line slightly above the center. The vertical line of the letter B is heavy and the loops projecting from this line are heavier at the center than at each end. The letter C is in the form of a curve, the line diminishing in thickness toward each end. The letter D is in keeping with the letter B and the single loop is heavier at the center than at the ends. The vertical lines of the letters E and F are heavy and the upper cross-lines and the middle lines are light, and the lower line of the letter E is also light. The letter G is in keeping with the letter C, and the two vertical lines of the letter H are heavy and the cross-line is light. The single line of the letter I is heavy. The line of the letter J is heavy and terminates in a tapered loop. The vertical line of the letter K is heavy, the upper inclined line is light, and the lower inclined line is heavy. The vertical line of the letter L is heavy and the lower line light. The right-hand line of the letter M is heavy and the left-hand line is light, while one diagonal line is heavy and the other light. The two vertical lines of the letter N are both light and the inclined line is heavy. The letter O is in the form of an oval, being heavy at each side and narrow at top and bottom. The vertical line of the letter P is heavy and the loop is heavy at the center and is tapered toward each end. The letter Q is in keeping with the letter O, but somewhat narrower, and an ogee-curved tail extends through the base of the letter. The letter R is similar to the letter P, with the addition of the inclined heavy line. The letter S is made of a double scroll heavy at the center and light at each end. The vertical line of the letter T is heavy and the cross-line is light. The letter U is in the form of a loop, the right-hand line is light, and the left-hand line heavy. In the letter V the right-hand inclined line is light and the left-hand inclined line is heavy. In the letter W the right-hand inclined line, as well as one of the central inclined lines, is light and the left-hand line and the other inclined line is heavy. In the letter X one of the inclined lines is light and the other heavy. In the letter Y the vertical line is heavy and the left-hand diagonal line is also heavy and the right-hand line is light. The inclined line of the letter Z is heavy and the upper and lower lines are light.

It will be seen that the letters have the corners well defined, giving a sharp square appearance to the font.

The lower-case letters and numerals are in keeping with the upper-case letters.

I claim—

The design for a font of Gothic type as herein described and as shown in the accompanying typographical impression.

In testimony whereof I have signed my name to this specification in the presence of two subscribing witnesses.

JOSEPH W. PHINNEY.
